UNITED STATES PATENT OFFICE

163,132

CONTAINER FOR DAIRY PRODUCTS AND SOFT DRINKS

Peter Muller-Munk, Pittsburgh, Pa., assignor to Otto Milk Company, Pittsburgh, Pa., a corporation of Pennsylvania

Application March 24, 1948, Serial No. 145,318

Term of patent 14 years

(Cl. D58—12)

To all whom it may concern:

Be it known that I, Peter Muller-Munk, a citizen of the United States, residing at Pittsburgh, in the county of Allegheny, State of Pennsylvania, have invented a new, original, and ornamental Design for a Container for Dairy Products and Soft Drinks, of which the following is a specification, reference being made to the accompanying drawings, forming a part thereof.

Figure 1 is a perspective view of a container for dairy products and soft drinks, showing my new design; and

The drawings are shaded solid in the upper portion to indicate contrasting color.

I claim:

The ornamental design of a container for dairy products and soft drinks, as shown and described.
